UNITED STATES PATENT OFFICE.

HARRY B. GARMAN, OF DETROIT, MICHIGAN, ASSIGNOR TO THE STEEL PRODUCTS COMPANY, OF CLEVELAND, OHIO, A CORPORATION OF OHIO.

DRAG LINK.

1,416,188.

Specification of Letters Patent. Patented May 16, 1922.

Application filed August 2, 1921. Serial No. 489,362.

To all whom it may concern:

Be it known that I, HARRY B. GARMAN, a citizen of the United States, resident of Detroit, county of Wayne, and State of Michigan, have invented new and useful Improvements in Drag Links, (Case B,) of which the following is a specification, the principle of the invention being herein explained and the best mode in which I have contemplated applying that principle, so as to distinguish it from other inventions.

My invention relates to drag links for use as a part of the steering mechanism of automobiles, and particularly to apparatus of this character of the weldless type. The illustrated type is also a floating type of drag link, i. e., the bearings are free to float inside the tube and thus to conform to any irregularities of the steering arm and axle arm balls. Particularly, the invention relates to mechanism of this character formed from steel tubing and provided with an appreciably thickened wall in a section where there is unusual strain in mechanism of this character and which is usually a weak section; viz, the plane of juncture of the body of the link with the usual end sockets; also, provided with sections of increased area in the planes of the usual ball openings formed in the end sockets. My invention also relates to an improved link in which the usual end plug may be rigidly retained relatively to the socket by means of the usual cotter-pins and yet accommodation provided for the central intersection of said plugs by the usual grease cups having screw-threaded connections with the plugs. Furthermore, the assembly provides mechanism in which the usual end grease cups are less liable to be knocked off the link when the same is used as a cross-tube or tie-rod.

The annexed drawing and the following description set forth in detail certain means embodying my invention, the disclosed means, however, constituting but one of the various mechanical forms in which the principle of the invention may be employed.

In said annexed drawing:

Figure 1 represents a broken central vertical section through a piece of tubing formed into my improved link;

Figure 2 represents a broken partial side elevation and partial central vertical section of a completely assembled link, including a

suggestion of the usual steering and axle arms;

Figure 3 represents a transverse vertical section, taken in the plane indicated by the line III—III, Figure 2;

Figure 4 represents a transverse vertical section, taken in the planes indicated by the line IV—IV, Figure 2; and

Figure 5 represents an end elevation, taken from the plane indicated by the line V—V, Figure 2.

Referring to the annexed drawing, in which the same ordinals refer respectively to the same parts in the several views, a piece of steel tubing is indicated by the ordinal 1, which has been upset and expanded in a forging machine so as to form the end sockets 2 having an outside diameter materially greater than that of the original tubing 1 and a section around the ball opening, hereinafter fully described, of an increased area. Shoulders 3 are thus provided which serve as seats at the inner end of sockets 2 for the parts usually associated with the steering arm and axle arm connections and which will be hereinafter more fully described. These operations result in greatly thickening the wall of the link in the sections of the shoulders 3; in forming the walls of the enlarged sockets 2 of a thickness equal to that of the original piece of tubing 1; and in strengthening the link in the sections 2' of the ball openings. These enlarged ball opening sections also allow for the drilling and tapping for grease cups at any angle. As plainly shown in Figures 1 and 2, the seats formed by the shoulders 3 are square, i. e., they have plane surfaces 4, but I do not limit myself to this form of seat, although I consider the same preferable, the invention being, however, broadly to the provision of a greatly thickened wall 3'.

The end sockets 2 are provided with the usual holes 5 for the reception of the balls of the connecting arms, said holes having the restricted portion 5' through which the ball cannot be drawn from the assembled link. These connecting arms are indicated by the ordinals 6 and 7 and the same are co-ordinated with the steering and axle mechanisms, respectively, as is well understood. These connections 6 and 7 are provided, respectively, with balls 8 and 9 which are

- journaled in blocks 10, these blocks being of an improved character and formed by the improved method of manufacture described and claimed in my companion application, 5 Serial No. 489,365, filed August 2, 1921, the usual springs 11 formed from round spring steel in the usual way being also provided. The assembly is retained in the socket 2 by means of externally-threaded end plugs 12 10 having engagement with the outer ends of said sockets 2. These plugs 12 are counter-bored, drilled and tapped and equipped with grease cups 13. The plugs 12 are held rigidly relative to the sockets 2 by means of 15 cotter-pins 14 and, in order that the plugs 12 may accommodate the grease cups 13 and still allow for the transverse intersection of the plugs 12 by the cotter-pins 14, I have counter-bored the plugs 12 as indicated by 20 the ordinal 15, and have spread the two arms 14' of the cotter-pins 14 in arcs above and below the grease cups 13, as plainly shown in Figure 5. This arrangement also enables so much of the grease cups 13 to be 25 accommodated within the plugs 12 as to provide more clearance for said cups so that the same are not so liable to be knocked off the link when the latter is used as a cross-tube or tie-rod. The blocks 10 are provided with 30 central holes 16 and communicating transverse grooves 17 for effectively passing the lubricant to the balls 8 and 9 and uniformly distributing the same upon the surfaces of said balls.
- 35 By reason of forming the sections 2' of increased area, I have greatly strengthened the link in the planes of the ball openings and have also provided means allowing for the drilling and tapping for grease cups to 40 be set at any desired angle as illustrated by cup 13' at the left hand end of Figure 2; also see Figure 4. In Figure 2, for purposes
- of illustration, I have shown the grease cups in both positions, i. e., cups 13 at the right end of the figure, intersecting plugs 12, and 45 cups 13' at the left end of the figure, mounted in enlarged areas 2'.
- What I claim is:
1. A drag link consisting of a piece of tubing having a socket portion of enlarged 50 diameter, said socket portion having a ball lever receiving slot therein, the wall of said socket portion being thickened at the slotted portion thereof.
  2. A drag link consisting of a piece of 55 tubing having a socket portion of enlarged diameter, a portion of the wall of said socket portion intermediate the ends thereof being thickened, said socket portion having a ball lever receiving slot therein, said slot having 60 an enlarged ball entering portion and a narrower ball retaining portion, the enlarged portion of said slot being formed in the thickened portion of the socket wall.
  3. The method of forming a drag link 65 which comprises upsetting an end portion of a piece of tubing to thicken the wall thereof, expanding said wall to enlarge the internal diameter thereof.
  4. The method of forming a drag link 70 which comprises expanding an end portion thereof to form an end socket of enlarged diameter and upsetting the metal at the inner end of the socket to form a thick walled shoulder.
  5. The method of forming a drag link, 75 which comprises upsetting and expanding an end of a piece of tubing to form an end socket of enlarged diameter, and upsetting the wall of the socket to form a circumferential reinforcing rib.

Signed by me this 23d day of June, 1921.

HARRY B. GARMAN.
